(57) **CLAIM**

The ornamental design for a molded cooler, as shown and described.

DESCRIPTION

FIG. 1 is a perspective view of the molded cooler showing my new design, the dashed line showing of the shoulder strap does not form a part of the invention;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.
